UNITED STATES PATENT OFFICE.

GEORGE E. MCWETHY, OF BARBERTON, OHIO, ASSIGNOR TO THE WRIGHT TOOL & FORGE COMPANY, OF BARBERTON, OHIO, A CORPORATION OF OHIO.

SOCKET SET.

Application filed August 18, 1927. Serial No. 213,800.

The present invention relates to a socket set and holder for use in conjunction with the usual and well known socket wrench set. Each of the wrench sets comprises a handle 5 and a set of sockets of various kinds which are adapted to be used selectively with the handle.

In using the wrench set, particularly in garages or machine shops, the mechanic quite 10 frequently requires the wrench and a number of the sockets of different sizes in order to make the proper selection. It is also quite difficult to keep a complete set of the sockets intact.

15 The present invention has for its object the design and construction of a holder for a set of sockets so that the mechanic can take a complete set with him to his location and also to insure against the loss of the sockets in a set. The device as shown is light and easily transported and is so arranged that the sockets will be firmly held in place frictionally and without a locking device to 20 secure them in position.

25 In the drawings, in which the preferred embodiment of the invention is shown:

Figure 1 is a plan view of the improved socket holder with the sockets removed;

Figure 2 is a side view showing sockets 30 in position; and.

Figure 3 is an enlarged section through a single socket holder on the line 3—3 of Figure 1.

The socket holder comprises a bar 5 of 35 the requisite length to hold a row of sockets, to which are attached a plurality of posts or holders 6, each post being shown as riveted in place on the bar so that the holders are rigidly mounted on the bar. These hold- 40 ers are preferably square in cross-section

and are slightly smaller than the interior of the socket 7.

Each holder is provided with a transverse opening 8 in which are mounted balls 9, held apart by a coil spring 10, the edges of the 45 metal about the opening being peened or riveted about the balls, as shown at 11, to retain them in position, slightly protruding beyond the outer surface of the posts. When a socket is forced over the post, the balls 50 are forced inwardly slightly so that the expansion of the spring grips the sockets firmly and holds them in position upon the bar.

By the use of the device, the mechanic can take a complete set of sockets to the job 55 and is enabled to select the particular sockets which he requires for the work at hand. He is always assured of a satisfactory holder for the sockets which are not in use. The invention is not necessarily limited to exact 60 conformity with the showing and description, but may be varied within the scope of the claim.

What is claimed is:

A socket set comprising an elongated flat 65 bar, a plurality of solid posts secured to one side of the bar at spaced intervals, a plurality of sockets, and means incorporated in each of said posts to hold a socket in position thereover with the socket freely removable from the post, said means comprising 70 two balls seated in a transverse passage in the upper portion of the post, a spring in the passage to force the balls outwardly so that they project beyond the opposite surfaces of the post, the mouths of the passage 75 being restricted to prevent escape of the balls when the socket is removed from the post.

GEORGE E. MCWETHY.
